UNITED STATES PATENT OFFICE.

JAMES INGRAM, OF NEW YORK, N. Y.

WATER-BACK FOR RANGES.

Specification forming part of Letters Patent No. 19,368, dated February 16, 1858; Reissued June 21, 1859, No. 738.

To all whom it may concern:

Be it known that I, JAMES INGRAM, of the city, county, and State of New York, have invented, made, and used certain new and 5 useful Improvements in Movable Water-Backs for Cooking-Ranges; and I do hereby declare that the following is a full, clear, and exact description of the construction and operation of the same, reference being 10 had to the annexed drawing, making part of this specification, wherein—

Figure 1, is a plan of a cooking range with the top plate removed to show my improved water back, and Fig. 2, is a vertical section 15 of the range near the center of the same.

Similar marks of reference indicate the same parts.

Many of the cooking ranges, both in the city and country, where a competent supply of water exists, are fitted with water backs to heat, by circulation, the water contained in a boiler standing near the said range. The water back, to be sufficiently operative, is in contact with the fire, and will 20 heat sufficient hot water for washing and other domestic purposes. When the range is being used for ironing, particularly, but little hot water is required, and an intense fire is in contact with the water back; hence it is 25 found practically that steam is often formed in the water back, that drives the water out of the adjoining boiler causing an overflow of the cistern (if one be used) and often collapsing the boiler and splitting the water 30 back when the cold water rushes into the boiler, condensing the steam, and running into the highly heated water back, injuring or splitting the same. Besides the foregoing difficulty with water backs, another 35 often arises in the country places when a continued drought exhausts the reservoirs or wells, and there is not sufficient for supplying the hot water boiler, in this case the range cannot be used for fear of burning 40 out the empty water back.

The nature of my said invention consists in setting the water back in such a manner that it can be slid away from the fire and a soap stone or fire brick or equivalent non- 50 conducting substance, introduced between the fire and the water back, thus obviating all the inconveniences and dangers before enumerated.

In the drawing *a*, is the fire place of any 55 desired character of range, *b*, *b*, the ovens.

The flues and other parts are to be of any character, and not relating to the water back need no further description.

c, is the water back shown in its usual place in Fig. 1, with the circulating pipes 60 *d*, *e*, to the boiler *f*.

g is the brickwork or setting of the range.

In almost all cases the distance between the boiler *f* and water back *c*, is such that the pipes *d*, *e*, will spring two or three 65 inches without disturbing the joints if the parts are otherwise unobstructed; I therefore fit my water back *c*, to slide on supports 1, 1, back and forth, and approach to or recede from the fire; and to move said 70 water back with facility I provide levers *h*, *h*, on fulcrums 2, 2, joined together by a rod 3, and connect said levers with the water back by links 4, 4. The space in which the water back moves is made tight by the bottom plate 5, and top plate 6, which is provided with a cover 7, to allow access to the levers *h*, to move the water back, the object 75 being to prevent heat being drawn under said water back by any draft.

When the water back has been drawn away from the fire a soapstone or fire brick (*i*), is to be inserted between the fire and said back and this may be placed in by hand and rest on a suitable ledge or support, or 80 the said stone or fire brick may be on one end of a lever *k*, on a fulcrum 8, and move up and down in the space *l*, (Fig. 2,) and be balanced by the weight 9, so that when the water back is moved to the rear the lever 85 and weight shall force up the intervening stone or brick, and when desired to increase the amount of heated water, the lever *k*, is to be acted on by the small rod 10, to depress the brick or stone while the levers *h*, *h*, are used to move the water back up to 90 the fire again.

My water back can thus be in contact with the fire when required, or almost instantaneously protected from the same in the 100 manner and for the purposes before enumerated. And besides the foregoing difficulties it will be proper to mention the fact, that in case any of the plumbing work in the house requires repairs so that the water 105 has to be let off, the fire in the range has to be extinguished and so remain until the repairs are completed, while with my movable water back the range can be in use all 110 the time whether there is water in the back

or not; and the water back can be moved as desired without disturbing the pipes, or requiring a range maker or plumber, the same being done by the occupants of the 5 house.

What I claim as my invention and desire to secure by Letters Patent is—

1. Arranging the water back and parts connected with and supporting the same in 10 substantially the manner specified, so as to allow the said water back to be moved away from the fire or be brought in contact with the same, without disturbing the pipes and

connections substantially as and for the purposes specified.

15

2. And in combination with said movable water back I claim the lever *k* and weight 9 to move the intervening soap stone or fire brick, substantially as specified.

In witness whereof I have hereunto set my 20 signature this fifth day of January 1858.

JAMES INGRAM.
